RAIL BRACE OR CLAMP.

1,216,339.

Specification of Letters Patent. Patented Feb. 20, 1917.

Application filed August 21, 1916. Serial No. 116,105.

To all whom it may concern:

Be it known that we, JOHN LEO McNEIL, DUNCAN B. McDONALD, and AUGUSTINE McDONALD, citizens of the Dominion of Canada, residing at Birch Grove, in the Province of Nova Scotia, Canada, have invented a new and Improved Rail Brace or Clamp, of which the following is a specification.

This invention is in the nature of an improved rail clamp device or attachment and while it is susceptible of a variety of uses, it is more especially adapted for furnishing a means of securing broken or split rails (when such occurs on the road and the fractured rail has not been replaced by a new one) so that a train may proceed and be not delayed by waiting for the replacing of the broken rail.

Primarily, our invention has for its object to provide a clamp device or attachment of the general character stated, of a simple and inexpensive construction, that may be readily carried on the engine, as is other emergency gear, such as replaceers, etc., whose application requires only a few moments time and which can be readily applied by the head end crew of the train.

Another object of our invention is to provide a rail attachment in which is embodied a special design of two part clamp having coöperative members for closing against the opposite sides of the web of the split or broken rail, and with the said members contacting at one point only and such point located at the lowest possible distance below the rail base, and which forms, as it were, a fulcrum or pivot relatively so positioned with respect to the rail web engaging faces of the said coöperating members, whereby, as the load transmitted through the rail to the clamp device is on, the load stress tends to increase the clamping characteristics of the opposing portions of the clamp that engage the broken rail web, which portions, in my construction of clamp are primarily held to their rail web clamping condition by draw bolts which engage the two opposing sections that constitute the clamp, at a point below the base portion of the rail.

We are aware that numerous rail clamping devices have heretofore been provided and designed for clamping the adjacent ends of rail sections or for clamping broken or split rails, but so far as we know such

clamping devices have not been found as meeting the desired requirements, especially emergency needs for quick and effective temporary repair of a broken rail section, since such devices as have heretofore generally been provided have been more particularly designed for being permanently applied, when set up and provided with special clamping elements adapted for extending across an adjacent pair of rail ties and spiked thereto.

Our invention differs from the general run of rail clamping devices in that the same can be applied on a broken rail at any point between an adjacent pair of rail ties, whose base is adapted for being embedded in the road bed, and which can be almost instantly secured to the rail, without need of drilling bolt holes or otherwise making ready the rail, and when applied, the co-operating parts do so engage the broken web portion of the rail that the load (as the train passes over the damaged rail) is transmitted directly on the temporary base bearing for the rail and in such manner that the clamping members of the said base bearing or clamp device are caused to close against the web portion only of the broken rail, and with no other part of the said clamp device in clamping engagement with the rail, special provision being also made for relieving the draw bolts of undue stress, sufficient clearance being given the sides of the body of the clamp, that contact of such sides, is impossible except at the pivot or fulcrum point contact at the extreme lower end or base of the clamp.

With other objects in view that will hereinafter appear our invention consists in the peculiar construction and novel arrangement of the parts hereinafter fully explained, specifically pointed out in the appended claims, and illustrated in the accompanying drawing, in which:

Figure 1 is a perspective view of a portion of a broken rail and our improved rail clamp operatively applied.

Fig. 2 is a cross section of the clamp applied to the rail.

Fig. 3 is a perspective view of the several parts that constitute our improved rail clamp, the said parts being shown separated.

The general shape and size of our rail clamping device relatively to the standard

type of rail will be readily apparent from the drawing.

The body of our improved rail clamp or attachment, is composed of two half sections 5 1-1 of like shape, either of which may be used as a right or left member when they are to be operatively applied to a rail.

The sections 1 are made of cast steel of sufficient strength to take the maximum load 10 to which a rail is subjected; without failure, either by flexure or shear in which it may be weakest.

Each section 1 includes a base portion, which, when the clamp is applied is set in 15 the road bed, and at the lowermost part the inner vertical face of the said base is formed with a convexed rib 2 that extends horizontally the full length of the section and projects beyond the said vertical face so that, 20 when the two sections are assembled, the two ribs 2 form the only point of contact between the two sections, (see Fig. 2) and thereby provide, as it were, a fulcrum or pivot point X located at the lowermost possible place below the rail.

The upper end of each section 1 terminates in a flat face clamping head 3 for engaging the web portion 40 of the rail 4, and it should be here stated the faces 3 of 30 the head are the only portions of our rail attachment that clamp against the rail.

Each clamping head has a recess 5 that extends outwardly from the inner face and along the full length of the section, and the 35 said recess is provided for receiving the base flange of the rail as is clearly shown in Fig. 2, by reference to which it will be seen that the base portions 50 of the recesses 5 are concaved on an arc having the fulcrum point x as the center, the reason for which 40 will presently appear.

The recesses 5 in which the rail base flanges 41-41 project are of sufficient clearance so that the clamping sections do not 45 contact with the rail at any place other than at the web and base portion thereof, as shown.

At a suitable point below the rail supporting portions 6-6, the sections 1-1 have 50 alining bolt apertures 7 that receive the draw bolts 8. Bolts 8 include a round head 80 with a neck portion 81 square in cross section that keeps the bolts from turning in their apertures 7 should the nuts 9 become 55 tight on their threads.

As is clearly indicated in Fig. 2, the bolt apertures 7 are sufficiently large to allow a limited loose fit of the bolts, the reason for 60 which will presently appear, and the outside profile of the clamp sections 1-1 are recessed as at 12 for seating the bolt heads and the nuts, as shown.

To decrease their weight and also to facilitate positioning the clamp into the road 65 bed and the consequent less removal of ma-

terial from the road bed when placing the clamp sections under and against the broken rail, the lower ends of the sections 1-1 are cut away, as at 13.

By reason of the peculiar and simple form 70 of the opposing clamp sections as described and shown, when the clamp device is needed, all that is necessary is to dig a shallow pocket in the road bed under the broken section of the rail, after which the two clamp 75 sections can be almost instantly seated in the pocket formed in the road, closed with their clamping heads against the web portion of the broken rail, and held to the initially clamped engagement with the said rail by 80 the draw bolts 8, it being obvious that in drawing the two sections 1-1 together their upper ends are caused to move up against the rail web since the contacting ribs now 85 serve as a fulcrum or pivot.

While the draw bolts 8 serve as the means 90 for primarily holding the clamping heads securely over the broken rail web, by reason of the relatively loose fit of the bolts through the bolt apertures, the said bolts are at no 95 time subjected to the load strain when the train passes over the broken rail, since by reason of the bolt apertures being of larger cross sectional area than the bolts there is sufficient play of the sections, toward each 100 other and relatively to the said bolt, that the load strain on the rail is taken up by the sections 1-1 since the tendency of the said sections 1-1, as the train passes over the clamped rail, is to swing the clamping heads 105 in the direction of the arrows y-y and thereby increase the characteristics of the clamping heads, it being understood that the load strain is transmitted directly to the two opposing sections through the tread of the 110 rail, as the said rail engages the sections in such a manner that they now tend to swing toward each other, and as the sections are supported on a ground base, it follows that there is practically no load strain taken up 115 by the draw bolts 8, as the clamping heads are now held against the broken rail web under a maximum pressure, as the train passes over the broken rail.

An important advantage in providing a 115 clamping device in which provision is made for taking off any of the load strain from the draw bolts, is that the bolts will not thereby be twisted or mashed in their apertures, and hence can be quickly disconnected 120 from the clamp by the crew after the train has passed over the broken rail to thereby allow for the quick removal of the said clamp device when used for emergency purposes only.

The clamp device shown in the drawing, in its practical arrangement is of sufficient depth to stand the greatest bending moment of the rail between the greatest distances of points of support with wrought 130

iron bolts of sufficient diameter to stand the greatest tensile stress liable to be exerted on them.

In practice, the clamp device is preferably fifteen inches long with three bolt apertures, the end ones being set two and one-half inches from the ends of the clamp; the distance between centers of the bolts being five inches.

10 From the foregoing description taken in connection with the drawing, the construction, the manner of its application and the advantages of our invention will be readily understood.

15 What we claim is:

1. An emergency rail clamp for broken or split rails, comprising a pair of like shaped coöperating members including base portions adapted to underlie the rail and rest on the road bed, the said members having portions for extending over the rail base flanges and for engaging the web of the rail and clamping the rail web only, the lowermost ends of the base portions having inwardly projected contacting ribs that serve as a fulcrum bearing between the opposing members each of the said members having a horizontal recess extending the full length thereof to loosely receive the rail flanges, the base of said recesses forming a chair for the rail base, means located below and out of contact with the rail for moving the heads of the opposing members to a clamping engagement with the rail web.

2. An emergency rail clamp for broken or split rails, comprising a pair of like shaped coöperating members including base portions adapted to underlie the rail and rest on the road bed, the said members having portions for extending over the rail base flanges and for engaging the web of the rail and clamping the rail web only, the lowermost ends of the base portions having inwardly projected contacting ribs that serve as a fulcrum bearing between the opposing members each of the said members having a horizontal recess extending the full length thereof to loosely receive the rail flanges, the base of said recesses forming a chair for the rail base, means located below and out of contact with the rail for moving the heads of the opposing members to a clamping engagement with the rail web, the bearing points of the rail on the two opposing members being such that the stress of the passing load on the rail is so transmitted to the opposing members whereby to effect a maximum clamping action of the head portions of the said members on the rail web without effecting the means that primarily hold the said head portions to their rail web clamping position.

3. An emergency rail clamp for broken or split rails, that comprises a rail chair consisting of two coöperating opposing mem-

bers including base portions for resting on the road bed and extending lengthwise of the rail, the said base portions being normally spaced apart and having portions on their adjacent lower faces that form horizontally extended contacts, the upper ends of the said members having horizontal recesses for loosely extending over the base flanges of the rail, and having head portions for clamping against the web of the rail, the base of the opposing recesses forming the seat for the rail, the said members having alining bolt apertures at points below the rail base, draw bolts coöperating with the said opposing members for effecting a primary contact of the head portions on the rail web, the bearing on the coöperative combined chair and clamp members being such relatively to the contacting lower ends of the said members, whereby to increase the clamping characteristics of the said heads when the load is on the rail.

4. An emergency rail clamp for broken or split rails, that comprises a rail chair consisting of two coöperating opposing members including base portions for resting on the road bed and extending lengthwise of the rail, the said base portions being normally spaced apart and having portions on their adjacent lower faces that form horizontally extended contacts, the upper ends of the said members having horizontal recesses for loosely extending over the base flanges of the rail, and having head portions for clamping against the web of the rail, the base of the opposing recesses forming the seat for the rail, the said members having alining bolt apertures at points below the rail base, draw bolts coöperating with the said opposing members for effecting a primary contact of the head portions on the rail web, the bearing on the coöperative combined chair and clamp members being such relatively to the contacting lower ends of the said members whereby to increase the clamping characteristics of the said heads when the load is on the rail, the said bolts being loosely fitted in the bolt apertures whereby the load strain on the chair is transmitted direct to the said clamping head on the broken web and the bolts thereby relieved of load stress.

5. As a new article, an emergency clamp for bracing broken or split rails comprising two coöperating members of like contour, each including a base portion adapted to rest in the road bed under the broken rail, a head portion having a clamp face for engaging the web of the rail, said head portion having recesses for loosely receiving the base flanges of the rail, each of the base portions of the said members being provided with a horizontally extended rib on its inner face, each of the said members having a bolt aperture below the rail receiving recess, bolts

and nuts for coöperating with the said apertures, the said apertures being of slightly larger diameter than that of the bolt, the said portions of the rail flange receiving recesses forming chair-like bearings for the rail, all being arranged substantially as shown and for the purposes described.

6. As a new article, an emergency clamp for bracing broken or split rails, comprising two coöperating members of like contour, each including a base portion adapted to rest in the road bed under the broken rail, a head portion having a clamping face for engaging the web of the rail and horizontal recesses for loosely fitting over the base flanges of the rail and provided with a hori-

zontally extending rib on its inner face, the bottom of the recesses that receive the base flanges of the rail being curved on an arc with the horizontal rib as the center, each of the said members having bolt apertures below the rail receiving recesses, bolts and nuts for coöperating with the said apertures, said apertures being of slightly greater diameter than the bolts, the base portion of the rail flange recesses forming chair-like bearings for the rail, all being substantially as shown and for the purposes described.
